United States Patent Office

Des. 211,832
Patented July 30, 1968

211,832

SPOON OR SIMILAR ARTICLE

Ellen B. Manderfield, Syracuse, N.Y., assignor to Oneida
Ltd., Oneida, N.Y., a corporation of New York

Filed June 9, 1967, Ser. No. 7,415

Term of patent 14 years

(Cl. D54—12)

FIG. 1

FIG. 2

FIG. 3

FIG. 4

FIG. 5

FIG. 6

FIG. 1 is a front view of a spoon showing my new design.

FIG. 2 is a rear view thereof.

FIG. 3 is a side view thereof, the undisclosed side being substantially identical with the side shown in FIG. 3.

FIG. 4 is an enlarged cross-section taken on line 4—4 of FIG. 1;

FIG. 5 is an enlarged cross-section taken on line 5—5 of FIG. 1; and

FIG. 6 is an enlarged cross-section taken on line 6—6 of FIG. 1.

I claim:

The ornamental design for a spoon or similar article, substantially as shown and described.
